WATCH WINDING MACHINE

John H. Gotter, Abilene, Tex.

Application September 28, 1951, Serial No. 248,746

7 Claims. (Cl. 81—7.5)

1

This invention relates to watch winding apparatus and more particularly to such apparatus which is automatic in the sense that the mechanism is set into motion to wind a watch through pressure applied by application of the winding crown of the watch to the winding head of the machine.

The principal object of the invention is to provide a watch winding machine designed to obviate the outstanding fault present in earlier machines for the purpose which is that of exerting torque beyond the force required to wind a watch, irrespective of size and ill equipped to control the applied torque. Early efforts to produce a successful watch winding machine have included, as a power medium, an electric motor, in which the torque controlling medium generally consists of a friction clutch adapted to slip after the watch spring has been wound. It has been determined by watch manufacturers, in actual practice that the friction clutch alone cannot be relied upon to limit the degree of torque supplied by an electric motor or, for that matter, the torque applied manually, hence a watch winding machine is needed in which the power source itself can be controlled and supplemented by a clutch which can be of the friction type.

It is therefore the chief object of the invention to provide a watch winding machine in which winding torque is supplied through the medium of a bladed impeller freely mounted on the winding shaft of the machine and adapted to be propelled by air under pressure released from an air nozzle by mechanism actuated by pressure imposed manually on the winding head of the machine. A friction clutch, under predetermined spring pressure maintains driving relationship between the impeller and winding shaft.

It is another object of the invention to provide a watch winding machine pneumatically actuated to apply sufficient torque to wind the springs of watches of different sizes without danger of overwinding and equipped with a torque control medium in the form of a friction clutch sufficiently sensitive to prevent overwinding of the more delicate watch spring, yet predetermining the torque necessary to wind the springs of watches of larger sizes.

With the foregoing objects in view, the invention has further reference to certain features of accomplishment which will become apparent as the description proceeds, taken in connection with the accompanying drawing wherein:

Figure 1 is a side elevational view of a watch winding machine constructed according to the

2

invention and in which parts are in cross-section, including the case.

Figure 2 is a sectional view taken on line 2—2 of Figure 1.

5 Figure 3 is a detailed sectional view taken on line 3—3 of Figure 1, and

Figure 4 is a detailed view of the yoke through which motion is transmitted from the winding head to actuate the air release valve.

10 Continuing with a more detailed description of the drawing, reference numeral 10 denotes the base consisting of a flat metal plate on which is mounted a front standard 11 and a rear standard 12, each standard being secured to the base 10 by means of screws 13. Standard 11 is equal in width to the base 10 while the standard 12 is narrower in width and is disposed midway between the sides of the base 10.

15 Adjacent the top of the standard 11 is a circular opening 14 on which is frictionally mounted a bushing 15 having a central bore through which extends a winding shaft 16. A ball race is provided in each end of the bushing 15, each race containing ball bearings 17 in which winding shaft 16 rotates. The outer end of the winding shaft 16 has a central bore 18 in which is disposed for limited longitudinal displacement an arbor 19. The arbor 19 has a longitudinal slot 20 which receives a transverse pin 21 extending through the drive shaft 16. This arrangement enables the arbor 19 to move longitudinally but constrains the arbor to rotate with the winding shaft 16.

20 Formed on the outer end of the arbor 19 is an annularly grooved enlargement 21. A chuck or winding head 22 is attached to the enlargement 21 by means of a threaded shank 23 formed on the winding head which enters a threaded bore in the center of the enlargement 21. The winding head 22 is hollow in order to receive a rubber plug 24.

25 The plug 24 has a coniform recess 25 in order to accommodate watches having crowns of different diameters. The plug 24 may be secured in the winding head 22 as by cementing or other suitable means.

30 In order to prohibit longitudinal displacement of the winding shaft 16, a collar 26 is affixed by means of a set screw 27 to the shaft in flush relationship to the rear face of the front standard level. This collar is made preferably of steel in order that it will have no affinity for the adjacent collar 28, which is preferably made of brass and which constitutes a clutch element, freely mounted on the winding shaft 16. At 35 tached to the collar or clutch element 28 by

means of screws 29 is an impeller consisting of a disc 30, formed on its outer periphery with a plurality of blades 31 perpendicular to the plane of the disc 30 and preferably turned at an angle to the rotating axis of the disc 30. Forming a part of the impeller and clutch is a collar 32, secured in the assembly by the screws 29 and bearing against the collar 32, through the medium of a plate 33, is a coil spring 34 surrounding the winding shaft 16. The opposite end of the coil spring 34 bears against a plate 35 which engages a ball bearing 36 arranged in a ball race 37, the latter being formed on the end of a sleeve 38 which is longitudinally movable in a retaining sleeve 39 and held against rotation therein by means of a pin 40 extending transversely through the sleeves 38 and 39 and a slot 41 in the sleeve 38. The sleeve 38 is interiorly threaded to receive the left-hand threads on the shank 42 of adjusting screw 43. The adjusting screw 43 carries a knurled knob 44 and is annularly grooved at 45 to receive a ball 46 which is held in the groove by a spring 47 and a set screw 48 in the top of the rear standard 11, to hold the adjusting screw 43 against other than rotative movement. By turning the knob 44 in a clockwise direction, the sleeve 38 will be moved in a forwardly direction to increase the tension on the coil spring 34, thus to increase the pressure imposed on the clutch element 28. Conversely, opposite rotation of the knob 44 will diminish the friction between the collar 26 and clutch element 28.

Torque is applied to the impeller 30 and thus to the winding shaft 16, by means of air under pressure supplied from a compressor, not shown, to the nipple 49 (Figure 2). Air enters the chamber 50 where it remains under constant pressure until the valve 51 is opened in the manner to be presently explained. The valve 51 seats on a rubber disc 52, which bears against a retainer 53 within the valve housing 54. The valve 51 is mounted on a valve stem 55 which extends forwardly through a collar 56, threaded into the upper end of the valve housing 54. A coil spring 57 surrounds the valve stem 55 within the collar 56, its lower end engaging a disc 58, held in place in the housing 54 by the lower end of the collar 56. The upper end of the spring 57 bears against an annular flange 59 formed on the valve stem 55 and which limits upward movement of the valve stem by engagement with an internal flange 60 formed on the upper end of the collar 56. When the valve stem 55 is depressed, air from chamber 50 will pass through the opening in the valve seat and retainer 53 and provided for the stem 55 and will enter a passage 61 formed in a lateral branch 62 of the valve housing and from this passage, the air will emerge from the nozzle 63 and will impinge the blades 31 of the impeller 30, thus to impart motion to the clutch element 28 and to the winding shaft 16 through the collar 26, with which the clutch element 28 is frictionally engaged. A needle valve 64 threaded into the end of the branch 62 of the valve housing provides an adjustment to predetermine the quantity of air released from the nozzle 63.

To actuate the valve 51, a yoke 65 (Figures 1 and 4) is disposed in the annular groove in the enlargement 21 formed on the arbor 19. This yoke has an arm 66 which extends downwardly and is secured by a screw 67 to the outer end of a push rod 68. The push rod 68 extends through an opening in the front standard 11 immediately below the winding shaft bushing 15. The inner

end of the push rod 68 carries a ball 69, freely rotatable in a socket in the end of the push rod and this ball bears against the upper end of a rocker arm 70. The arm 70 is pivoted at 71 to a bifurcated mounting 72, attached by means of a screw 73 to the inner surface of the front standard 11. The arm 70 has formed thereon a finger 74 having a lobular end 75 which bears against the upper end of the valve stem 55.

It is clearly evident from the foregoing that pressure exerted inwardly on the winding head 22 will cause the yoke 65 to move inwardly, resulting in similar movement of the push rod 68. The rocking arm 70 will be actuated to cause the finger 74 to bear downwardly on the valve stem 55, opening valve 51, releasing air through the nozzle 63 against the impeller blades 31, to rotate the winding shaft 16, which, in turn, rotates the winding head 22 to rotate the crown of a watch disposed in the conical recess of the plug 24. To minimize friction, the yoke 65 is provided with a series of balls 76 which are set in openings extending entirely through the yoke so that the balls will engage both walls of the annular groove in the enlargement 21 of the arbor 19.

To support a watch in position for winding, platform 77 is mounted on a plate 78 by means of screws 79. A supporting means for the plate 78 consists of a plug 80 which is secured by means of screws 81 to the front standard 11 immediately under the push rod 68. The plug 80 is tapped and threaded to receive a screw 81, whose lower end is provided with a knurled knob 82. The upper end of the screw 81 has a longitudinally threaded bore adapted to receive a screw 83 or equivalent means which is affixed against movement in the screw 81. The screw 81 extends through an opening 84 in the plate 78 and the head of the screw 83 is disposed above the plate 78 and, being larger than the opening 84, will move the plate downwardly when the screw 81 is rotated in a counter-clockwise direction. The annular shoulder 82 adjacent the upper end of the screw 81 bears against the underside of the plate 78 and exerts upward force on the plate to raise the same when the screw 81 is rotated in a clockwise direction. It is apparent that the arrangement shown may be employed or the screw 83 may be substituted by simply peening the upper end of the adjusting screw 81. In this manner, the watch supporting platform 77 is raised and lowered in relation to the winding head 22 to accommodate watches of different thicknesses and sizes. The guide rod 85 depends from the plate 78 on each side of the adjusting screw 81, to support the platform 77 in a horizontal position. The platform 77 is provided on each side of its center with a recess 86 to accommodate the fingers while the watch to be wound is held in position to engage its winding stem crown with the winding head 22.

It is apparent that watches with or without wrist bands can be supported with equal facility on the platform 77 since there is nothing under the platform which would interfere with a wrist band.

There is some noise attending the operation of the machine, due to the release of air from the nozzle 63. To reduce this noise, shell 87 is designed to embrace the rear portion of the machine, its forward edge being secured by means of screws 88 to the top and sides of the front standard 11. A vertical slot 89 is provided in the rear of the case 87 to accommodate the clutch adjusting shaft 43. A noise damping lining 90

of rubber or other suitable composition is applied to the inner surfaces of the piece 87.

To accommodate a suitable instrument for adjusting the needle valve 64, an opening 91 is made in one wall of the case 31 in alignment with the valve 64 and on the opposite side, an opening 92 is provided in the case for the passage of a hose or pipe for conveying air from the compressor to the nipple 43 of the valve housing 54.

In operation, a watch to be wound is placed on the platform 77 so that the crown of its winding stem will enter the coniform recess 25 in the winding head 22. Slight inward pressure imposed by the watch against the winding head will cause longitudinal inward displacement of the arbor 19, thus actuating the yoke 65 to tilt the arm 78 through the medium of the push rod 66. The finger 74 of arm 78 will bear downward on the valve stem 55, opening valve 51, releasing air through the nozzle 63, which is directed towards the impeller blades 31, thus rotating the winding shaft 16, which, in turn, rotates the winding head 22 to wind the spring of the watch through its stem.

Manifestly, the construction as shown and described is capable of some modification and such modification as may be construed to fall within the scope and meaning of the appended claims is also considered to be within the spirit and intent of the invention.

What is claimed is:

1. In a machine for winding watches, a frame, a winding shaft journaled in said frame, a winding head on said shaft, an arbor carrying said winding head capable of limited longitudinal displacement axially with respect to said winding shaft, a fixed clutch member on said winding shaft, a movable clutch member spring biased into frictional engagement with said fixed clutch member, a bladed impeller affixed to said movable clutch member, an air chamber in which is maintained air under constant pressure, a nozzle communicating with said air chamber and directed towards said impeller, a valve normally closing said nozzle against release of air from said chamber, a rocking arm pivoted to said frame having a finger engaging said valve, a push rod for actuating said rocking arm and means depending from said arbor and actuated upon displacement of said winding head to move said push rod and rocking arm to open said valve to release air through said nozzle against the blades of said impeller to rotate said winding shaft and head.

2. In a watch winding machine, a frame, a winding shaft journaled in said frame, a winding head mounted axially on one end of said shaft for limited inward displacement under pressure of a watch stem against said head, a bladed impeller freely mounted on said winding shaft, a nozzle for directing air under pressure against the blades of said impeller, a valve normally closing said nozzle against release of air, a yoke movable horizontally by displacement of said winding head, a rocking arm having a finger engaging said valve means actuated by said yoke upon inward displacement of said winding head to tilt said rocking arm to open said valve and release air against said impeller through said nozzle and means frictionally joining said impeller and winding shaft to rotate said winding head.

3. In a watch winding machine, a frame, a

- rotatable shaft supported in said frame, an arbor rotated by said winding shaft and capable of limited longitudinal movement in relation thereto, a winding head on said arbor, an air actuated impeller freely mounted on said shaft, a clutch element fixed to said shaft, a companion clutch element fixed to said impeller and freely mounted on said shaft, adjustable spring means normally urging said clutch elements into frictional engagement, a nozzle directed towards said impeller through which air under pressure is directed against said impeller to drive said shaft, valve means normally closing said nozzle against release of air, a valve actuating arm, a push rod for operating said arm and means depending from said arbor and engageable with said push rod to move said valve actuating arm to cause said valve to open to release air through said nozzle.
- 10 4. The structure of claim 3, and a vertically adjustable support for a watch disposed in winding position in relation to said shaft.
- 15 5. The structure of claim 3, and a case on said machine having a lining composed of a material having the property to dampen the noise of exhaust of air from said nozzle.
- 20 6. A watch winding machine including a winding shaft mounted in a frame, an arbor rotated by and movable longitudinally with respect to said winding shaft, a longitudinally reciprocable winding head carried by said arbor against which the winding stem of a watch is urged for rotation, an air actuated impeller on said shaft, an air nozzle directed towards said impeller, means for supplying air to said nozzle under pressure to rotate said impeller, a valve normally closing said nozzle, a valve actuating arm pivoted to said frame, a push rod for operating said arm, means depending from said arbor and actuated by pressure on said winding head to move said push rod and open said valve to discharge air against said impeller to rotate said shaft and means for predetermined the degree of torque applied to said shaft by said impeller.
- 25 7. A watch winding machine including a winding shaft mounted in a frame, an arbor rotatable by said winding shaft and having a winding head thereon against which the winding stem of a watch is urged for rotation, an air actuated impeller on said shaft, an air nozzle directed towards said impeller, means for supplying air to said nozzle under pressure, a valve normally closing said nozzle, a yoke depending from and actuated by said arbor, a valve actuating arm pivoted to said frame, means disposed between said yoke and valve actuating arm effective to open said valve to discharge air from said nozzle against said impeller to rotate said shaft when pressure is imposed by a watch on said winding head and means for predetermined the degree of torque applied to said shaft by said impeller.
